COMBINED BRUSH AND COMB CONSTRUCTION

Filed Aug. 20, 1931

UNITED STATES PATENT OFFICE

ALFRED F. REILLY, OF NORTH ATTLEBORO, MASSACHUSETTS, ASSIGNOR TO EVANS CASE COMPANY, OF NORTH ATTLEBORO, MASSACHUSETTS, A CORPORATION OF MASSACHUSETTS

COMBINED BRUSH AND COMB CONSTRUCTION

Application filed August 20, 1931. Serial No. 558,256.

This invention relates to a hair brush construction and, with regard to its more specific features, to a means for retaining an article within a hair brush.

One of the objects of this invention is to provide a device of the above character which will be simple, practical and thoroughly durable. Another object of this invention is to provide a device of the above character which will be of ready manufacture and pleasing in appearance. Another object is to provide a device of the above character which will be compact and convenient for traveling. Another object of this invention is to provide a brush with means for retaining a toilet article therein and for releasing such article when desired. Other objects will be in part obvious and in part pointed out hereinafter.

The invention accordingly consists in the features of construction, combinations of elements, and arrangements of parts, all as will be illustratively described herein and the scope of the application of which will be indicated in the following claims.

In the accompanying drawing, in which is shown one of the various possible embodiments of my invention,

Figure 1 is a top plan view of a brush, showing the article, such as a comb, ready to be removed therefrom;

Figure 2 is a vertical cross-sectional view as seen along the line 2—2 of Figure 1;

Figure 3 is a horizontal sectional view taken along the line 3—3 of Figure 2, showing the parts in their closed position;

Figure 4 is a vertical transverse sectional view taken along the line 4—4 of Figure 2; and

Figure 5 is a vertical transverse sectional view taken along the line 5—5 of Figure 3.

Similar reference characters refer to similar parts throughout the several views of the drawing.

Referring now to the drawing, I have provided, as is better shown in Figure 1, a brush-carrying back 10 extending from which is a handle 11. As is more clearly shown in Figure 2, brush back 10 is preferably of sheet metal and has an annular flange 13 extend-

ing downwardly and inwardly to retain a member 14 carrying bristles 15 of the brush, thus forming a strong and compact brush body. Member 14 may take any convenient shape and may be constructed of any material suitable for retaining brush bristles as, for example, wood or a suitable rubber composition. At its lower side (Figure 2), the inner end of handle 11, also of sheet metal and hollow, is formed into a flange 16 which abuts against the right hand end of member 14 and, as more clearly shown in Figure 4, flange 13 extends along the longitudinal sides and along the left hand end (Figures 2 and 3) of brush back 10, thus cooperating with end 16 to hold member 14 securely to the brush back 10 and handle portion 11.

Referring to Figures 3 and 4, there is shown a channel 17 cut into the top of member 14 and extending longitudinally thereof from the left hand end of brush back 10 and in substantial alignment with the interior of hollow handle 11. As is best shown in Figures 2 and 4, a sheet metal guide 18 of inverted U-shaped cross-section lies within channel 17 and extends through and to the end of handle 11, the top wall 24 thereof preferably resting against the under side of brush back 10 which is preferably spaced from part 14. Guide 18 has two side walls 19 and 20 (Figure 4) extending downwardly from the under side of brush back 10 to substantially the bottom of channel 17; it is secured in place in any suitable manner. For example, the left hand end of guide 18 may be secured to brush back 10 as by soldering, generally indicated at 21 (Figures 2 and 3). The other or right hand end of guide 18 is similarly secured to the end wall 11a of the handle 11 through which there is a rectangular opening 22 with which it registers. Thus by the provision of sheet metal member 18, a longitudinal guide channel generally indicated at 23 (Figures 2 and 4) is provided extending from the opening 22 in handle end 11a, through handle 11 and through brush back 10 and member 14 to the left hand end of the brush, being made up of top wall 24 and side walls 19 and 20 of member 18 and having a base consisting of the bottom of channel 17 in member 14.

Slidably received within channel 23 is a casing-like member 25, as is more clearly shown in Figures 2, 4 and 5, being substantially U-shaped in cross-section and having its bottom wall 25a resting against the bottom of channel 17 and the bottom side of opening 22 in handle 11 (Figure 2). Side walls or flanges 26 and 27 of member 25 extend upwardly and lie within and against side walls 19 and 20 respectively of guide 18. In this manner, member 25 is free to slide within channel 23 and is dependably guided by the latter.

Suitably positioned and fitted within the inner or left hand end of guide 18, as viewed in Figures 2 and 3, is a spring 28 interposed between the respective end walls 18b and 25b of guide 18 and member 25. Spring 28 may be and preferably is secured to members 18 and 25 in any convenient manner, but preferably a middle portion 29 of the end wall 18a of guide 18 is cut out and bent so that one end of the spring, which is preferably of flat stock (see Figure 2) may rest between it and the remaining portions of the end 18b. Spring 28 may also be and preferably is secured to member 25 in a similar manner, as is more clearly shown in Figure 3. Spring 28 is constructed to tend to expand, thus acting against member 25 to force it to the right and in a direction out of channel 23 to permit member 25 to assume the position shown in Figure 2. Member 25 is shorter than channel 23 (Figure 3) so that sufficient space is left within the channel to accommodate spring 28 when compressed, as when member 25 is moved and held completely within channel 23 in a manner to be described hereinafter.

Hingedly secured as at 31, to the right hand end of member 25, as viewed in Figures 2 and 3, is a member 30, the bottom wall 30d of which is substantially an extension of the bottom wall 25a of member 25. Member 30 has side walls 30a and 30b (Figure 1) forming extensions of side walls 26 and 27 of member 25, and an end closing wall 30c of substantially the same dimensions as the opening 22 in handle end 11a. Thus member 30 forms an end portion of slidable guide member 25 when member 25 is in its left hand position as shown in Figure 3. But when member 25 is pushed toward the right and partially out of the channel 23, due to the action of spring 28, member 30 drops down to the position shown in Figure 2, moving the closing wall 30c out of obstructing position. Within the slidable carrier or casing 25-30 is fitted a companion toilet article, illustratively a comb 12, which is preferably equal in length to the combined lengths of member 25 and member 30 and, as the latter parts assume the position shown in Figures 1 and 2, a portion of comb 12 is left exposed

so that it may be grasped by the user and withdrawn from the casing 25.

To form the base of that portion of channel 23 that is within handle 11, there is provided a sheet metal member 32 (Figures 2 and 3) secured to the bottom end of opening 22 and preferably to the depending side walls 19 and 20 of member 18. The inner or left hand end of member 32, as viewed in Figures 2 and 3, is cut away as at 33 and pivotally mounted at substantially the inner or right hand end of the recess thus formed is a lever 34. Lever 34 may be pivoted to swing about a pin 36 secured to the portions of member 32 lying upon the opposite sides of recess 33 (Figure 3). Mounted upon or integral with the right hand end of lever 34, as viewed in Figure 2, is a catch 37, and member 32 is cut out as at 32a so that catch 37 may pass therethrough for coaction with the bottom 25a of member 25 and to form a cut out downwardly bent tongue portion 38 which rests against the under side of lever 34 and hence against catch 37 on lever 34 to act as a spring and press the catch upwardly against the base of member 25. At a suitable point in the bottom 25a of member 25 is a slot 35 (Figures 2 and 3) shaped to receive catch 37 when member 25 is in its closed position, as shown in Figure 3.

When member 25 is pushed to the left from the position shown in Figure 2 to the position shown in Figure 3, catch 37 snaps into slot 35 to hold member 25 in this position and to hold closing end portion 30 with its end wall 30c closing the opening 22 in handle end 11a, all against the action of spring 28. Secured to the left hand end of lever 34, as best shown in Figures 2 and 3, is a button 39 extending through a suitable opening in the lower wall 11b (Figure 2) of handle 11. When member 25 with comb 12 therein is in its inner position, thus retaining and housing comb 12, and when the use of the comb is desired, pressure exerted against button 39 acts against the resilient pressure created by tongue portion 38 of member 33 to release catch 37 from slot 35 and thus allow spring 28 to force member 25 partially from channel 23. The parts then assume the position shown in Figure 2, for member 30 drops down to expose the end of comb 12 so that it may be grasped for removal by the user. Spring 28, being preferably secured to both fixed and slidable parts 18 and 25, limits the extent of automatic withdrawal of part 25.

It will thus be seen that there is provided a thoroughly practical, efficient construction in which the several objects and advantages hereinabove mentioned, as well as many others, are successfully achieved. Furthermore, it will be seen that many common inconveniences met with especially in travel are successfully overcome.

As many possible embodiments may be

made of the above invention and as many changes might be made in the embodiment above set forth, it is to be understood that all matter hereinbefore set forth or shown 5 in the accompanying drawing is to be interpreted as illustrative and not in a limiting sense.

I claim:

1. In a device of the character described, 10 in combination, a brush having a recess in its body, means located within said recess for retaining an article, and means for actuating said retaining means to release said article from said brush.

15 2. In a device of the character described, in combination, a brush having a recess extending through its body, a container in said recess of substantially the shape of said recess for retaining a comb therein, and means for 20 forcing said container partially from said recess.

25 3. In a device of the character described, in combination, a brush having a recess extending through its body and handle, containing means for a comb in said recess, means for ejecting said containing means with said comb at least partially from said recess, and manually actuated means for controlling said ejecting means.

30 4. In a device of the character described, in combination, a brush having a longitudinal recess extending through its body and handle, containing means for a comb adapted to fit within said recess, means for retaining said containing means within said recess, and means for releasing said containing means from said recess.

35 5. In a device of the character described, in combination, a brush, a recess in said brush, containing means for an article within said recess, means for projecting said containing means from said recess, and manually actuated means for controlling said last-mentioned means.

40 6. In a device of the character described, in combination, a brush having a recess extending through its body, containing means for a comb located in said recess, means for releasing said containing means from said recess, and means for controlling said releasing means.

45 7. In a device of the character described, in combination, a toilet article having a recess therein, means containing a comb adapted to fit within said recess, means for forcing said containing means from said recess, means acting against said forcing means to lock said containing means within said recess, and manually actuated means for controlling said last-mentioned means.

50 8. In a device of the character described, in combination, a toilet article having a recess therein, retaining means for a comb located in said recess, resilient means acting upon 55 said retaining means, and means for con-

trolling the action of said resilient means and said retaining means.

9. In a device of the character described, in combination, a brush having a recess extending through the body and handle thereof, a 70 flanged member adapted to fit within said recess for holding a comb therein, resilient means for forcing said member partially from said handle, and manually actuated means for controlling the action of said resilient means.

10. In a device of the character described, 75 in combination, a brush having a recess extending through the body and handle thereof, means for retaining a comb within said recess, a spring adapted to force said comb from said recess, a latch adapted to lock said means within said recess, and manually actuated spring retarded means for controlling the action of said latch.

80 11. In a device of the character described, in combination, a brush having a recess extending through the body and handle thereof, means for retaining a comb within said recess, a spring adapted to force said comb partially from said recess, and manually actuated means for controlling the action of said spring, said last-mentioned means being located upon the under side of said handle substantially near the junction of said handle 85 and said body.

12. In a device of the character described, 90 in combination, a brush having a recess in the body thereof, means for retaining an article within said recess, resilient means for forcing said retaining means from said recess, and a latch adapted to lock said retaining means within said recess.

100 13. In a device of the character described, in combination, a brush having a recess in the body thereof, means for retaining an article within said recess, resilient means for forcing said retaining means from said recess, a latch adapted to lock said retaining means within said recess, and manually actuated means for controlling the action of said latch.

105 14. In a device of the character described, in combination, a brush having a recess extending through the body and handle thereof, a flanged member adapted to fit within said recess and having a hinged portion forming one end thereof, means for retaining said member within said recess, means for releasing said member from said recess, and manually actuated means for controlling said last two mentioned means.

110 15. In a device of the character described, in combination, a brush having a recess extending through the body and handle thereof, a flanged member adapted to fit within said recess and having a hinged portion forming one end thereof, said member adapted to hold a comb, a spring seated within said body and acting against said member to 115 120 125 130

force said member partially from said handle, a latch adapted to lock said member within said recess against the action of said spring, and manually actuated spring retarded means for controlling the action of said latch.

16. In a device of the character described, in combination, a brush, sheet metal containing means for an article within the body 10 of said brush, and means for forcing said containing means partially from said body so that it may be grasped.

17. In a device of the character described, in combination, a brush, a portion of the 15 body of which is formed from sheet metal, said brush having a recess formed from sheet metal extending through its body, a sheet metal container in said recess of substantially the shape of said recess for retaining 20 a comb therein, and means for forcing said container partially from said recess.

18. In a device of the character described, in combination, a brush, a portion of the body and handle of which are formed from 25 sheet metal, said brush having a sheet metal recess extending through the body and handle thereof, a sheet metal flanged member adapted to fit within said recess and having a hinged portion forming one end thereof, 30 means for retaining said member within said recess, means for releasing said member from said recess, and manually actuated means for controlling said last two mentioned means.

19. In a device of the character described, in combination, a brush body having a longitudinal recess therein, containing means for an article, said containing means fitting within said recess, means for releasing said containing means partially from said recess, and means for preventing the entire displacement of said containing means from said recess.

20. In a device of the character described, in combination, a brush body, a longitudinal recess in said brush body, a hollow metal part 45 for holding an article, said part fitting within said recess, means for retaining said part within said recess and partially releasing said part from said recess, and means for preventing the complete release of said part from said recess.

21. In a device of the character described, in combination, a brush body, a longitudinal slot in said brush body having one end open, 55 a hollow part slidably fitting within said slot, said part having a hinged end portion, means for releasing said part from said slot so that said hinged portion may drop downwardly and expose an article within said part, and means preventing the complete release of said part from said slot.

22. In a device of the character described, in combination, a brush comprising a body and a handle having a longitudinal slot running therethrough, one end of said slot being

open, a hollow part for containing an article slidably fitted within said slot, releasable means adapted to retain said part in said slot, and means for preventing the complete release of said part from said slot when said 70 releasable means is actuated.

23. In a device of the character described, in combination, a brush including a body and handle having a longitudinal recess extending therethrough, a hollow metal part slidably fitted within said recess, said recess having one open end, an end portion hingedly secured to the under side of said hollow part, a spring disposed between the opposite end of said hollow part and the corresponding 80 end of said recess, said spring adapted to force said hollow part partially through said opening so that said end portion may drop downwardly and expose an article in said part, and a spring-pressed latch adapted to 85 coact with a slot in said hollow part for holding said hollow part totally within said recess, said latch adapted to be manually actuated to release said hollow part.

24. In a device of the character described, in combination, a brush including a body and handle having a longitudinal recess extending therethrough, a hollow metal part slidably fitted within said recess, said recess having one open end, an end portion hingedly secured to the under side of said hollow part, a spring disposed between the opposite end of said hollow part and the corresponding 95 end of said recess, said spring adapted to force said hollow part partially through said opening so that said end portion may drop downwardly and expose an article in said part, and a pivoted latch member adapted to coact with a slot in said hollow part to hold said part within said recess, a portion of the 100 bottom wall of said recess extending over one end of said latch member to force said latch member toward said hollow part.

In testimony whereof, I have signed my name to this specification this 14th day of 110 August, 1931.

ALFRED F. REILLY.
